US00D488166S

(12) **United States Design Patent** (10) Patent No.: **US D488,166 S**
(45) Date of Patent: ** Apr. 6, 2004

(54) **SOUND AND VIDEO TRANSMISSION DEVICE**

(75) Inventor: **Wilfried Johan Paul Ferdinand Daniels, Sint Truiden (BE)**

(73) Assignee: **Koninklijke Philips Electronics N.V., Eindhoven (NL)**

(**) Term: **14 Years**

(21) Appl. No.: **29/181,552**

(22) Filed: **May 13, 2003**

(30) **Foreign Application Priority Data**

Nov. 13, 2002 (WO) DMA/005 888

(51) LOC (7) Cl. **14-03**

(52) U.S. Cl. **D14/496; D10/104**
